UNITED STATES PATENT OFFICE

ROBERT WESEMAN, OF SPOKANE, WASHINGTON

SAW SET

Application filed May 21, 1929, Serial No. 364,762. Renewed February 10, 1932.

My invention relates to saw-sets and certain objects of the invention are to provide a saw-set that is adapted for manual operation by foot and hand, which embodies means for setting saw teeth at predetermined angles together with adjustable means whereby the angles may be changed as desired, and which embodies adjustable means for regulating the length of the plunger stroke and adjustable means for setting the base block at different heights.

With the above and other objects in view which will appear as the description proceeds, the invention consists of the novel construction, adaptation, combination and arrangement hereinafter described and claimed. These objects are accomplished by devices illustrated in the accompanying drawings; wherein;

20 Fig. 1 is a view in perspective of the machine as a whole;

Fig. 2 is a top plan view of the complete machine;

Fig. 3 is an enlarged view in perspective of the main operating parts of the machine;

Fig. 4 is a view in central vertical section of the same.

Referring to the drawings throughout which like reference numerals designate like parts, the numeral 5 indicates the rear legs and 6 indicates the forward legs which are convergently disposed and the four legs are held in spaced relation and triangular disposition by three upper frame members 7 and 30 in rectangular disposition at their lower portions by four frame members 8. A seat 9 is mounted on said upper frames where they convergently join the forward legs for convenience of the operator.

40 The rear legs 5 slant inwardly to the upper frames 7 and their portions above said frames, as designated by the numeral 10, are vertically disposed as clearly shown in Fig. 1 of the drawings. Said rear legs and their

45 upper portions are provided with vertical slots 11. A base block 12, having depending side plates 13, has its corner portions slidably disposed within the angular leg portions 10 and thumb screws 14, slidably disposed in said vertical slots, are threaded into

said side plates thus providing means whereby said block may be adjustably raised or lowered as will be understood.

The block 12 is stepped by a cut away portion at 15 and its lower step 16 is provided with a countersunk anvil 17 of hard metal, while its upper step 18 has a bracket 19 secured thereto in support of a spring casting 20. A wedge shaped plunger 21, disposed vertically above said anvil and passing centrally through said spring casing, is provided with an annular shoulder 22, and an expansion spring 23 housed within the casing bears against said shoulder and retains said plunger in a normally raised position.

A connecting rod 24 is secured to the upper portion of the plunger 21 by means of a connecting link 25 passing through one end of the link or hole 26. Said connecting rod may be shifted to any position and locked in place by a set screw 26' for the purpose of giving a longer or a shorter stroke to the plunger in a downward movement of said connecting rod as will be understood. The connecting rod has a relatively long vertical portion which extends downwardly and slidably through a guide sleeve bracket 27 fixed to the block 12 and thence to connection with a foot lever 28 that is pivotally connected to a fixed cross bar 29. It will be obvious that pressure applied to the foot lever will move the plunger downwardly to engagement with the anvil 17 and when same is released the spring 23 will raise said plunger to its normal position.

My means for giving slant to the saw for proper setting of its teeth comprises a lower stationary member 30 and an upper adjustable member 31. The lower member is secured and built into lower block step 16. The upper member 31 is inserted into a horizontal slot 32 of member 30. The member 31 is slidable in a horizontal plane and is held in rigid alinement by tightening the thumb screw 33. A threaded bolt 34 is securely fastened to the member 31 and projects vertically thru slot 34' supporting thumb screw 33.

The upper slidable member 31 is provided with a horizontal slot 37. A screw rod 35 which is threadedly disposed thru the member

30 is provided with an annular shoulder 36, which coacts with slot 37.

By loosening the thumb screw 33 the member 31 is free to be adjusted thru the operation of the screw rod 35 by turning the knob 38.

In the operating of my device, a saw such as shown at 39, is placed in the position shown in Fig. 4 with its teeth directly under the plunger 21 and one of its sides resting on the slidable upper member 31 in a horizontal disposition. By pressing on the foot lever 28 and moving the saw along by hand plunger may be made to turn every other tooth outward and by turning the saw over the remaining teeth may be turned outwardly in the opposite direction. If a coarser set of the saw teeth is desired for the purpose of sawing a wider kerf the upper member 31 is moved outwardly by turning the screw knob 38 to the right thus giving a greater slant to the saw and a finer set may be made by turning said knob in the opposite direction as will be understood.

Referring to Fig. 3 of the drawings, I usually provide a scale such as shown at 40 on the stationary member 30 and an index mark 41 on the slidable member 31. Thus, in moving said slidable member the pitch or setting of the saw teeth may be predetermined by shifting said slidable member until its index mark registers with any number or mark on the scale to give the desired setting.

Having thus described my invention, it being understood that minor changes in its construction may be resorted to without departing from its scope and spirit, what I claim and desire to secure by Letters Patent of the

United States is:-

A sawset comprising a frame, upwardly projecting spaced apart angular members for the frame, a base block, depending side plates for said block, the corners of said block slidably disposed within the angular frame members, clamping means for said side plates whereby the base block may be adjusted to various heights, a foot lever, a plunger, a connecting rod between the lever and plunger, a connecting link between the plunger and connecting rod, adjusting means for said link, spring means for retaining the plunger in a normally raised position, an anvil slidably disposed in a groove in the base block and having a beveled inner portion, adjusting means whereby said anvil may be moved inwardly and outwardly with respect to the plunger, and screw clamping means for the anvil.

In testimony whereof I affix my signature.

ROBERT WESEMAN.
